UNITED STATES PATENT OFFICE.

JOSEPH DOTY, OF WELLSVILLE, NEW YORK.

CORNER-IRON.

SPECIFICATION forming part of Letters Patent No. 380,871, dated April 10, 1888.

Application filed December 8, 1887. Serial No. 257,302. (No model.)

To all whom it may concern:

Be it known that I, JOSEPH DOTY, of Wells-ville, in the county of Allegany and State of New York, have invented a new and Improved 5 Corner-Iron, of which the following is a full, clear, and exact description.

My invention relates to an improvement in the mode of constructing the corners of carriage-bodies, carriage-seats, and other structures in which two or more boards are required to meet at any angle and be firmly attached to form a corner either round, square, oblique, or angular.

The invention consists in the construction 15 and combination of the several parts, as will be hereinafter fully set forth, and pointed out in the claims.

Reference is to be had to the accompanying drawings, forming a part of this specification, 20 in which similar letters of reference indicate corresponding parts in all the figures.

Figure 1 is a plan view of a corner constructed in accordance with my improvement. Fig. 2 is a longitudinal section on line xx of 25 Fig. 1, and Fig. 3 is a transverse section on line yy of Fig. 2.

Square and angular corners have heretofore chiefly been formed by mitering and nailing the boards together, and round corners by 30 steaming boards of certain varieties of wood and bending them as required. Corners made in this wise are insecure and open upon the first severe strain.

In the construction of round corners as at 35 present only a limited variety of woods can be employed as set forth above, and expensive formers and other appliances are necessary in the manipulation of the woods. By reason of these facts the bodies of vehicles and vehicle-40 seats requiring round corners cannot be made in small shops and must be purchased from large firms making a specialty of such work.

It is the prime object of this invention to overcome the difficulties above set forth and 45 provide a means whereby any ordinary skilled mechanic may join two boards of any kind of wood and of any length or thickness and form a corner, either round, square, or angular, that shall be firm, neat, and durable and at a minimum cost, and also wherein all the plugging 50 and putting of screw-heads or nail-heads so

common in all mitered structures will be dispensed with.

In carrying out the invention, A represents a metallic corner, which, while represented as 55 semicircular, may be made of any desired shape, and preferably of either cast or wrought iron. Parallel with each longitudinal edge a of the body A', and a distance therefrom, a rib, B, is cast, which ribs project inward sufficiently to bring their edges in the same plane with the longitudinal edges of the body. The major portion of the ribs is at angle to the body of the corner-iron, as shown in Fig. 3, the inner edges, b , of the said ribs being bent outward in the direction of longitudinal edges of the body A', as illustrated in Fig. 2, and by dotted lines, Fig. 3. Thus a mortise, b^2 , is formed at each side of the iron, adapted to receive, respectively, one end of the boards to 60 be joined and to firmly clamp the same. The ribs B do not extend the entire length of the body, but terminate a distance from the bottom, where they are united by a horizontal transverse partition, D, which partition is 65 provided with a central integral reduced projection, d . Parallel with the aforesaid partition D, and integral with the end of the body A', a similar partition, D', is formed, between which partition D and D' the bottom 70 board or boards of the structure are held. Near the top an inwardly-beveled recess, e , is cut in the flange b of the ribs to receive the ends of the girt adapted to support the seat. At the top of the corner-iron the ribs B are 75 connected by a cap, E, provided with a circular aperture, E', whereby a socket is formed for the reception of a whip, or stakes to be used in connection with additional side-boards, or for the standards of a canopy-top or equivalent structure.

In constructing the corner of a vehicle-body, for instance, the side and end boards, M M', are inserted in the respective mortises b^2 and held therein by screws entered through the ribs, or 85 in any other approved manner. The bottom board or boards, M², being held between the partitions D and D', preferably by bolts passing through the same, the girts N are secured to the side and end boards of the body at proper 90 distance from the upper edge, terminating, respectively, in the recesses e , as illustrated.

Having thus described my invention, what I claim as new, and desire to secure by Letters Patent, is—

1. A corner-iron consisting of a body having longitudinal side mortises, spaced partitions at the lower end, and an apertured cap, substantially as set forth.

2. A corner-iron consisting of a body, longitudinal ribs integral with said body near the outer edges and provided with an outwardly-inclined flange, a horizontal partition connecting the ribs at the bottom, a parallel horizontal partition forming the base of the body and spaced from the partition connecting the ribs, substantially as shown and described, and for the purpose herein set forth.

3. A corner-iron consisting of a body, longitudinal ribs integral with said body near the outer edges and provided with an outwardly-inclined flange, whereby side mortises are formed, a horizontal partition connecting the ribs at the bottom, a parallel horizontal partition forming the base of the body and spaced from the partition connecting the ribs and a cap-plate integral with the body, and ribs at the top provided with a central circular aperture forming a socket, all combined as and for the purpose herein set forth.

JOSEPH DOTY.
